[57] ABSTRACT

An acceleration responsive switching device which comprises a casing having, at its bottom portion, a reverse cone-shaped inner wall, a weight ball movably put in the casing and normally positioned on said reverse cone-shaped inner wall at its central portion, a switch means provided in the casing at the center of the bottom portion and being normally in contact with said weight ball and adapted to be disengaged from the contact with said ball when the ball is upwardly moved along an inclined face of said reverse cone-shaped inner wall due to an acceleration given. The present switching device is exactly and instantaneously responsive to an excessive acceleration, thereby enabling the traffic accident to be effectively avoided. The device is simple in construction and easy to manufacture at a reasonable cost.

ACCELERATION RESPONSIVE SWITCHING DEVICE

This invention relates to a switching device, and more particularly to a switching device adapted to be provided in a movable body such as a motor car and actuated responsive to an acceleration exceeding a predetermined level.

Recently, rapid increase of road vehicles has incurred many traffic accidents. In order to avoid such accidents, safety devices such as safety belt and air bag provided in a motor car have been put into practical use. Of such safety devices, the rolling-up type safety belt and the air bag respectively employ a locking device and an exploder device which are adapted to detect an acceleration of the motor car.

In known forms of acceleration responsive switching devices, especially in those utilizing a weight ball, the weight ball having a magnetic permeability is used to detect an acceleration by making use of magnetic flux change caused by movement of the weight ball. Such conventional devices require a number of parts and are complicated in structure, leading to high cost of manufacturing. Such conventional devices need also a relatively long time to detect an acceleration and are lack of instant responsiveness.

An object of this invention is to provide an acceleration responsive switching device which is simple in construction and exactly and instantaneously responsive to the acceleration.

Another object of this invention is to provide an acceleration responsive switching device of the character described, which requires a reduced number of elements or parts in constructions.

These and other objects, features and advantages will be apparent to those skilled in the art from the following detailed description and the appended claims.

Essentially, according to the present invention, there is provided an acceleration responsive switching device which comprises a casing having, at its bottom portion, a reverse cone-shaped inner wall, a weight ball movably put in the casing and normally positioned on said reverse cone-shaped inner wall at its central portion, a switch means provided in the casing at the center of the bottom portion and being normally in contact with said weight ball and adapted to be disengaged from the contact with said ball when the ball is upwardly moved along an inclined face of said reverse cone-shaped inner wall due to an acceleration given.

This invention will now be more particularly described with reference to the accompanying drawings in which:

FIG. 1 shows a vertically sectioned elevation of an acceleration responsive switching device embodying this invention;

FIG. 2 is a bottom view of the device shown in FIG. 1;

FIG. 3 shows a vertically sectional elevation of another acceleration responsive switching device embodying this invention; and

FIG. 4 is a sectional view of the device shown in FIG. 3 taken along the line IV-IV.

Like portions and parts are designated by like numerals in FIGS. 1 to 4.

Referring now to FIGS. 1 and 2, there is shown an acceleration responsive switching device which com-

prises a cylindrical casing 1 having, at its bottom portion, a reverse cone-shaped inner wall 3. The casing 1 is closed with a closure 4 threadedly fitted into said casing 1. The casing 1 has also a mounting plate 2 connected integrally therewith at the outer cylindrical side wall and adapted to be mounted on a vertical plane in the interior of a motor car at a suitable place.

In the interior of the casing 1 is movably put in a weight ball 5 which is normally positioned on the inner wall 3 of the bottom at its lowest or central portion.

The casing 1 is provided with a vertical opening 6 at the central portion of the bottom wall. Into said vertical opening 6 is slidably inserted a pushing rod 8 for movement in vertical directions. The pushing rod 8 has an upper surface 9 of a spherical shape to be snugly in contact with spherical surface of the weight ball 5 put in the casing 1. In the normal position, the upper surface of the pushing rod 8 forms a part of the inner surface of the bottom wall. Said pushing rod 8 has also a bottom which is supported on a self-returning push button 11 and is provided at its center with a small hole to be engaged with the upper end of said self-returning push button 11 which extends from a microswitch 10 fixedly mounted on a suitable place, for example on a support plate 7 as shown in FIGS. 1 and 2. The support plate 7 is formed integrally with the casing 1 and the casing mounting plate 2, and extends from both of the bottom wall and said casing mounting plate in a vertical plane at a distance from the hole 6.

The closure 4 in the casing has an inner wall having a profile to leave a space in the casing 1 to allow the weight ball to slide upwardly along the inclined face of the bottom wall. The inner wall of the closure 4 has at its central portion a downwardly projecting part 13 which prevents the weight ball from jumping up at the central position. The closure 4 is similarly constructed and functions in another embodiment as in FIGS. 3 and 4.

In operation, when an acceleration is given to a device-carrying motor car in a direction perpendicular to the vertical axis of the casing 1, namely in a horizontal direction, the weight ball 5 is slidably moved upwardly along the inclined face 3 of the bottom wall. Then, the weight ball 5 moves from the upper surface 9 of the pushing rod 8. As a result, a pushing force is released from the rod 8. Therefore the pushing rod 8 is urged upwardly by the returning force of the pushing button 11 to allow the latter to move upwardly, whereby off-operation of the switch is completed. Once the acceleration decreases below a predetermined level, the weight ball 5 moves downwardly to give a pushing force onto the upper surface of the pushing rod 8. The pushing rod 8 is pushed down to in turn urge the push button 11 downwardly, whereby the microswitch is caused to turn on (normal position).

FIG. 3 and 4 show another embodiment of this invention. The illustration of the same components or parts as employed in the foregoing embodiment is omitted to avoid repetition.

The casing 1 is not necessary to be provided with members such as the support plate 7 and the central opening as shown in FIG. 1. Instead, there are employed, at the bottom wall of the casing, two or more electric contacts 12, 12' connected to an electrical circuit (not shown) as depicted. The upper ends of the

electric contacts are placed closely onto the inner face 3 and normally in contact with the weight ball 5. In operation, a horizontal acceleration is given to a device-carrying motor car to move the weight ball 5 in the same manner as described referring to FIG. 1 and 2 and when the acceleration exceeds a predetermined level the weight ball 5 is caused to disengage from the connection with at least one of the electric contacts 12, 12' whereby the electrical circuit which is closed through the electric contacts 12, 12' and the weight ball 5 of electrical conductive material is now forced to open. With a drop of acceleration, the weight ball 5 is returned into contact with the contact surfaces of both electric contacts 12, 12'.

What is claimed is:

1. An acceleration responsive switch device, comprising:

casing means including a bottom wall portion having an upwardly facing and upwardly diverging conical support surface, said bottom wall portion having an opening extending substantially vertically therethrough substantially at the apex of said conical support surface;

a ball movably supported on said support surface, the weight of said ball normally maintaining same at the apex of said conical support surface; and

electrical switch means adapted to be actuated by said ball when same is moved toward to or away from said apex, said switch means including actuator means movably positioned within said opening and positioned for engagement with said ball when said ball is located at said apex, said actuator means being depressed by said ball when said ball

is located at said apex.

2. A switch device according to claim 1, wherein said switch means comprises a microswitch having a push button for actuating same, and said actuator means including a push rod slidably disposed within said opening and having the upper end thereof positioned for engagement with said ball, the lower end of said push rod being interconnected with said button for actuating same.

10 3. A switch device according to claim 2, wherein said push button is disposed in engagement with the lower end of said push rod, said push button urging said push rod upwardly so that the upper end thereof projects beyond said conical support surface when said ball is moved upwardly along said support surface away from said apex.

4. A switching device according to claim 2, wherein the upper end of said push rod has an upper surface having a spherical shape compatible with the spherical configuration of said ball.

20 5. A switching device according to claim 1, wherein said casing means includes an upper wall portion disposed above and spaced from said bottom wall portion so as to define a chamber therebetween in which is positioned said ball, and said upper wall portion having projection means fixedly secured thereto and projecting downwardly therefrom toward said apex, said projection means being disposed closely adjacent said ball when same is positioned at said apex for preventing said ball from moving vertically upwardly away from said support surface.
